UNITED STATES PATENT OFFICE.

ROBERT W. JOHNSON, OF CHICAGO, ILLINOIS.

DESIGN FOR A COLLAR-LINK.

58,237.

Specification for Design.

Patented June 28, 1921.

Application filed December 3, 1920. Serial No. 428,137. Term of patent 7 years.

To all whom it may concern:

Be it known that I, ROBERT W. JOHNSON, a citizen of the United States, residing at Chicago, in the county of Cook and State of Illinois, have invented a new, original, and ornamental Design for a Collar-Link, of which the following is a specification, reference being had to the accompanying drawing, in which a perspective view of the design is shown as applied to a collar, (Figure 1,) and a larger perspective view, (Fig. 2,) of the article itself.

I claim:—

The ornamental design for a collar link, as shown.

In testimony whereof I affix my signature.

ROBERT W. JOHNSON.
